UNITED STATES PATENT OFFICE

GUY JOSEPH HOUTS, OF OAK PARK, ILLINOIS, ASSIGNOR TO WESTERN ELECTRIC COMPANY, INCORPORATED, OF NEW YORK, N. Y., A CORPORATION OF NEW YORK

DEVICE FOR SUPPORTING AND DISTRIBUTING STRANDS

Application filed April 27, 1935. Serial No. 26,064.

This invention relates to devices for supporting and distributing strands, and more particularly to a device for supporting and distributing cables interconnecting telephone apparatus.

When interconnecting electrical apparatus such as is employed in telephone exchanges, it is frequently the practice to assemble the individual electrical conductors or cables, passing from one group of apparatus to another, into units, commonly called cable runs, which are attached to and supported by suitable framework. Especially when interconnecting groups of telephone apparatus, it has been the practice, in some instances, to fasten the interconnecting cables to each other and to the framework by means of textile strands, such as twine. Due to its character, this method is called sewing, and is somewhat slow and requires experience and a high degree of skill on the part of the workman.

The object of the present invention is to provide an improved device for readily and efficiently supporting and distributing strands or cables interconnecting telephone apparatus.

In accordance with one embodiment of the invention, the cables interconnecting two groups of telephone apparatus are arranged, at one point, in vertical rows upon a suitable support. Each vertical row is supported and maintained between spaced members which are secured to the support. At another point, the distributed rows of cables are assembled into groups having the cables arranged in vertical and horizontal rows which are maintained between spaced members also secured to the support.

Other features of the invention will become apparent in the following detailed description, reference being had to the accompanying drawing, wherein

Fig. 1 is a perspective view of a portion of a distributing frame, such as is frequently employed in telephone exchanges for supporting telephone apparatus, illustrating the improved method of and framework for supporting and distributing cables interconnecting telephone apparatus, and

Figs. 2, 3 and 4 are detail views of portions of the improved framework.

Although the invention is herein illustrated and described as particularly adapted to supporting and distributing cables interconnecting telephone apparatus, it should be understood that the novel features thereof may be adapted to other applications and that the invention is to be limited only by the scope of the appended claims.

Referring now to the drawing in detail, and particularly to Fig. 1 thereof, 10 indicates generally a portion of a distributing frame such as is frequently employed in telephone exchanges for supporting telephone apparatus such as terminal strips, one of which is indicated schematically at 11. The frame 10 comprises, essentially, a plurality of vertical angle irons 12 which are interconnected and rigidly supported at the top by a horizontal angle iron 13. Suitably supported by the frame 10 is a horizontal run of cables 15 which is formed into a plurality of vertical rows of cables 16 supported by suitable apparatus such as indicated generally at 17. The method of and apparatus for forming and supporting these vertical rows of cables is fully disclosed in the copending application of Guy J. Houts et al., filed April 27, 1925, Serial No. 26,063.

Suitably supported at one end by the frame 10, and at their other end by an angle iron 20, are a plurality of horizontally disposed parallel bars 21. The angle iron 20 is secured at the top of a plurality of vertical I-beams 23, only one of which is shown in the drawing. A plurality of channel irons 24, 25 and 26 are supported across the bars 21 and are conveniently spaced from each other to form a suitable support for a plurality of horizontally disposed cables 27 which, in the present embodiment of the invention serve to interconnect telephone apparatus supported by the frame 10 and I-beams 23.

A plurality of loop members 30, in the form of inverted U's and preferably composed of half round metal stock (Fig. 4) are suitably fastened to the channels 24, 25 and 26.

26. The loop members positioned at each end of the channels 24, 25 and 26 may be in the form of inverted V's such as indicated at 32 (Fig. 1). Each loop member 30 comprises a pair of parallel vertical portions 33, 33 which are connected at the top by a horizontal portion 35 (Fig. 3). The lower ends 36 of the vertical portions 33 are bent at right angles to provide means whereby the loop members may be welded or otherwise secured to the channels.

In the present embodiment of the invention, the cables 27 turn from vertical runs such as indicated at 38 (Fig. 1) and are formed in vertical rows such as 40, 41 and 42 around arcuate shaped members 43 (Fig. 2) which are fastened to the channel 24. Each vertical row is rigidly supported, at one point, between the vertical portions 33 of the loop members secured to the channel 24. At another point, the cables of several vertical rows are assembled together in suitable formation between the loop members secured to the channel 25, preferably, by first assembling the cables in each row into units comprising vertical and horizontal rows and then superposing said units to form a group such as indicated at 45 in Fig. 1. The group of cables thus formed is rigidly supported between the vertical portions 33 of adjacent loop members secured to the channels 25 and 26.

It should be noted that the loop members 30 may be suitably spaced from each other to accommodate any predetermined number or size of cables, and that they present only rounded surfaces to the supported strands or cables, thereby avoiding the possibility of injuring them or their covering by rubbing, scraping, etc.

It is obvious that no particular skill or experience is required in supporting and distributing strands or cables by the improved method and framework since they may be readily and rigidly assembled in position without the use of tools or twine and may be quickly removed from their assembled positions, when desired.

What is claimed is:

50. 1. In an arrangement for confining a group of cables in a channel consisting of a support, a plurality of spaced loop members secured to the support and having portions cooperating with oppositely disposed portions of an adjacent loop member to provide spaced open channels.

2. In a cable arrangement, a support, a plurality of spaced loop members secured to the support and having portions cooperating with oppositely disposed portions of adjacent loop members to provide a plurality of spaced open channels, a group of cables confined within each of said channels and converging therefrom into a common group, and cooperating members secured to the sup-

port for retaining the cable within the common group.

3. In a cable arrangement, a support, a plurality of horizontal and vertical layers of cables thereon, means attached to the support for confining the cables to a single group, and means for diverting the cables in different paths including elements forming open channels with one element common to two of the channels.

4. In a cable arrangement, a support, a plurality of horizontal and vertical layers of cables thereon, spaced upright members attached to the support for confining the cables to a single group, and means for diverting the vertical layers in different paths including elements forming open channels with one element common to two of the channels.

In witness whereof, I hereunto subscribe my name this 15th day of April, A. D. 1925.

GUY JOSEPH HOUTS.
